UNITED STATES PATENT OFFICE.

HARRY E. ASBURY, OF MELROSE PARK, PENNSYLVANIA, ASSIGNOR TO THE ENTERPRISE MANUFACTURING COMPANY OF PENNSYLVANIA, OF PHILADELPHIA, PENNSYLVANIA, A CORPORATION OF PENNSYLVANIA.

GRINDING MILL.

Application filed December 11, 1922. Serial No. 606,249.

To all whom it may concern:

Be it known that I, HARRY E. ASBURY, a citizen of the United States, residing in Melrose Park, Montgomery County, Pennsylvania, have invented certain Improvements in Grinding Mills, of which the following is a specification.

My invention relates to certain improvements in means for adjusting the grinding mechanism of a mill in order to regulate the fineness of the product being ground.

The invention is especially adapted for use in coffee mills, where different grindings are required, viz., coarse grinding; fine grinding and pulverizing.

The object of my invention is to design the adjusting means so that an operator can adjust the disks to several different positions, thus insuring the proper grinding of the material.

The invention also relates to certain details of construction, which will be fully described hereinafter.

In the accompanying drawings:

Fig. 1 is a longitudinal sectional view of sufficient of a grinding mill to illustrate my invention;

Fig. 2 is a sectional view on the line 2—2, Fig. 1;

Fig. 3 is a detached perspective view of the back plate of the mill;

Fig. 4 is a perspective view illustrating details of the adjusting means; and

Fig. 5 is a perspective view illustrating the ball bearing used in connection with the adjusting means.

Referring to the drawings, 1 is the base of the mill on which is mounted a frame 2 to which is attached the back plate 3. 4 is a horizontal shaft connected to the shaft of the electric motor shown by dotted lines 5, which is secured to the flange 6 of the frame 2. 7 is a hopper having a sliding gate 8 for controlling the flow of material to the mill.

9 is a hub splined to the shaft 4. This hub is in the form of a feed screw for feeding the material from the hopper to the space between the two grinding disks 10 and 11 provided with toothed ribs for grinding the coffee bean, &c.

The disk 10 is secured to the frame 2 and has an opening 12 for the passage of material. The disk 11 is secured to the hub 9 and is mounted between the hub and a disk

13. Longitudinal screws 14 firmly secure 55 the three parts together. The disk 13 has an extension 15, which has its bearings in the back plate 3. A spring 16 bears against the front end of the hub 9 and tends to force the disk 11 away from the disk 10. 60

17 is a ball carrier, in which is a series of anti-friction balls 20. The ball carrier is located between washers 18 and 19 in the back plate 3. Back of the washer 19 is a disk 21 having a projection 22 adapted to a 65 groove 23 in the back plate, which prevents the disk turning, yet allows it to move freely in a longitudinal direction.

25 is an adjusting screw, which extends through an opening 26 in the rear of the 70 back plate and bears against the washer 21. Mounted on the screw 25 is a cam disk 27 having a pin 28, which extends into the groove 23 so as to prevent the disk from turning when the screw is turned. On turning the screw, the disk acts as a nut.

The disk 27, as shown in Fig. 4, has three cam surfaces 29, which are in contact with cam surfaces 30 on a ring 31 mounted back of the disk 27. This ring bears against a 80 washer 32 at the end of the extension of the back plate, as shown clearly in Fig. 1. The opening in the ring 31 is enlarged so as to clear the screw 25. Secured to the ring 31 is a headed screw 33, which extends through 85 a slot 34 in the extension of the back plate, as shown in Fig. 3. On this screw is a handle 35. Between the head of the screw and a flange on the handle is a spring 36, which tends to force the conical end 37 of the 90 handle into the enlarged beveled portions 38 of the slot 34 so that the handle will hold the ring in position after adjustment.

When it is desired to adjust the disk 11 in respect to the fixed disk 10, all that is 95 necessary is to raise the handle 35 clear of the enlargement 38 of the slot 34 and move the handle laterally in one of the three positions indicated by the enlargements 38. On releasing the handle, it seats itself in 100 the enlargements and retains the ring in the position in which it is adjusted. This movement causes the cam surface 30 of the ring to move on the cam surface 29 of the disk 27, moving the disk longitudinally. As the 105 disk bears upon the end of the hub carrying the grinding disk 11, it will alter the position of the disk 11 in respect to the disk 10.

While my invention is especially adapted for use in connection with coffee mills where fixed grades of grinding are desired, it will be understood that the invention can be used 5 with other mills where it is desired to regulate the position of the grinding disks.

Although three cam surfaces are shown on the disk 27 and ring 31, a single cam surface may be formed thereon, or more than 10 three cam surfaces may be used, depending upon the size of the machine and the use for which it is intended.

In grinding coffee, three grades are usually required, but it will be understood 15 that the cam ring 31 may be set in any position. The handle 35 may be modified without departing from the essential features of the invention.

I claim:

20 1. The combination in a mill, of a casing; a fixed disk secured to the casing; a shaft extending part way through the casing; a disk mounted on the shaft and capable of being turned with the shaft but longitudinally adjustable thereon; a cam ring in the casing beyond the end of the shaft; a cam disk arranged face to face with the cam ring; means for preventing the rotation of the disk, but allowing it to move longitudinally 25 to adjust the movable disk on its shaft; and means for turning and locking the cam ring in the position to which it is adjusted.

2. The combination in a mill, of a casing; a grinding disk secured to the casing; a shaft; a hub on the shaft; means for connecting the hub with the shaft so that it can slide longitudinally thereon and will turn 30 with the shaft; a grinding disk secured to the hub; a back plate; a disk mounted in the

back plate in line with the hub; a screw 40 bearing against the back plate; a disk mounted on the screw; means for preventing the disk from turning, said disk having a cam surface; a ring having a cam surface bearing upon the cam surface of the disk; 45 and a handle attached to the disk, the back plate being slotted for the passage of the handle, said handle having a movable portion provided with an extension, the slot in the back plate being enlarged at intervals 50 for the reception of the enlargement of the handle so as to lock the disk in position after adjustment.

3. The combination in a mill, of a casing; a fixed grinding disk secured to the casing; 55 a longitudinal shaft; a hub on the shaft; a grinding disk secured to the hub; a back plate having an extension; a ball carrier mounted in the extension; a disk on each side of the carrier, one disk bearing against 60 the hub; a non-rotatable disk bearing against the other disk; a screw bearing against the last mentioned disk; a cam disk threaded for the reception of the screw; means for preventing the cam disk from 65 turning, but allowing it to move longitudinally; a cam ring mounted back of the cam disk and held from longitudinal movement by the rear of the back plate; a screw secured to the ring, the back plate having a 70 slot through which the screw extends; and a spring-pressed handle mounted on the screw, the walls of the slot being recessed to receive the end of the handle so as to lock the ring in the position in which is is adjusted. 75

HARRY E. ASBURY.
